CLAIM

The ornamental design for an audio signal controller, as shown and described.

DESCRIPTION

FIG. 1 is a top, front and right side perspective view of an audio signal controller showing my new design;

FIG. 2 is a top, rear and left side perspective view thereof; FIG. 3 is a bottom, rear and right side perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken line illustrate portions of the audio signal controller that form no part of the claimed design.
